(57) **CLAIM**

The ornamental design for a woman's undergarment, as shown and described.

DESCRIPTION

FIG. 1 is a front perspective view of an woman's undergarment showing my new design;

FIG. 2 is a front elevational view thereof;

FIG. 3 is a rear elevational view thereof;

FIG. 4 is a right side elevational view thereof, the left side being a mirror image thereof;

FIG. 5 is a top plan view thereof, shown as it would look when worn by a wearer (not shown);

FIG. 6 is a bottom plan view thereof, shown as it would look when worn by a wearer (not shown);

FIG. 7 is a front elevation view, shown in the flattened condition, at an enlarged scale; and,

FIG. 8 is a rear elevation view thereof.

The broken line showing of the human figure in FIGS. 1 and 4 is for illustrative purposes only and forms no part of the claimed design.

The tight broken line showing on the undergarment in FIGS. 1-8 represents stitching.

The fragmentary criss-cross pattern shown in FIGS. 1-8 represents fabric and is repeated uniformly throughout the areas shown.

The fragmentary stippled pattern shown in FIGS. 1-8 represents mesh fabric and is repeated uniformly throughout the areas shown.
